PANTY GIRDLE COMBINATION

Abraham Lustgarten, New York, N. Y.

Application February 9, 1949, Serial No. 75,439

3 Claims. (Cl. 2—43)

1

This invention relates to new and useful improvements in a removable crotch piece for ladies' undergarments.

More particularly, the invention proposes the construction of a crotch piece for use with a lady's undergarment, such as a girdle, corset, foundation garment or the like, which is completely removable and which can be worn with complete comfort when mounted in position on the garment.

Another object of the present invention proposes the construction of a removable crotch piece which can be used with any garment designed to encircle the bottom portion of the torso of the human body and which is constructed of a piece of cloth arranged to be extended beneath the crotch of the wearer in a manner to have its end portions extended upwards along the inside faces of the front and rear wall portions of the undergarment.

Still another object of the present invention proposes a novel means for releasably attaching the end portions of the crotch piece to the inside faces of the front and rear wall portions of the undergarment in a manner so that the crotch piece may be completely separated from the undergarment to be washed separately from the undergarment, when the crotch piece becomes soiled, so as to reduce the number of washings to which the undergarment need be subjected resulting in an increased life for the undergarment.

A further object of the present invention proposes providing elastic straps which have their ends attached to the top corners of the end portions of the crotch piece so as to encircle the top portions of the legs beneath the undergarment in a manner to assist the releasable attaching means in supporting the crotch piece in position.

A still further object of the present invention proposes forming the crotch piece with a narrow intermediate portion for extension beneath the crotch of the wearer in a manner to reduce the number of folds that will be formed when the crotch piece is mounted in position.

The present invention further proposes a novel means for vertically adjustably mounting the end portions of the crotch piece on the inside faces of the undergarment so that the vertical position of the crotch piece with relation to the undergarment can be adjusted to a desired comfortable position.

Still further, the present invention proposes a novel means for permitting the operative length

2

of the elastic straps to be adjusted in a manner to be comfortably engageable about the tops of the legs of different circumferences.

It is a further object of the present invention to provide a new and improved removable crotch piece of a lady's undergarment which is simple and durable and which can be manufactured and sold at a reasonable cost.

For further comprehension of the invention, 10 and of the objects and advantages thereof, reference will be had to the following description and accompanying drawings, and to the appended claims in which the various novel features of the invention are more particularly set forth.

15 In the accompanying drawings forming a material part of this disclosure:

Fig. 1 is a perspective view of a lady's girdle having a removable crotch piece constructed in accordance with the present invention.

20 Fig. 2 is an enlarged partial vertical sectional view taken on the line 2—2 of Fig. 1.

Fig. 3 is an enlarged partial front elevational view of the undergarment with the rear end portion of the crotch piece in a lowered position.

25 Fig. 4 is a perspective view of the crotch piece, per se.

Fig. 5 is a partial enlarged sectional view taken on the line 5—5 of Fig. 4.

30 Fig. 6 is a view similar to Fig. 2, but illustrating a modification of the present invention.

Fig. 7 is a partial inside elevational view looking in the direction of the line 7—7 on Fig. 6.

35 Fig. 8 is another view similar to Fig. 2, but illustrating the undergarment constructed in accordance with a still further modification of the present invention.

Fig. 9 is a perspective view of the crotch piece, per se, used in the form of the invention shown in Fig. 8.

40 The removable crotch piece, according to the form of the invention shown in Figs. 1 to 5, is shown applied to a lady's undergarment 20 designed to encircle the lower portion of the human torso and which has a front wall portion 21 and rear wall portion 22. On the drawings, the undergarment 20 is illustrated in the form of a girdle formed of two-way stretch elastic material having a front panel 23 of non-elastic material and the usual stocking garter members 24 secured

45 to the bottom edges thereof at the front and back. This illustration of a girdle is by way of example only, as the removable crotch piece of the present invention is equally well adapted for use in corsets, foundation garments and other similar types of undergarments.

3

Further details of the construction of the undergarment 20 will not be given in this specification as such details form no part of this invention and are generally known to those skilled in the art to which the present invention pertains.

The crotch piece 25 is formed of a blank of cloth material having a narrow intermediate portion 26 and a front end portion 27 and a rear end portion 28. The rear end portion 28 is wider than the front end portion 27 and the intermediate portion 26 is narrower than either of the end portions. The crotch piece is positioned with the narrow intermediate portion 26 extended beneath the crotch of the wearer, with the front end portion 27 extended upward along the inside face of the front wall portion 21 of the undergarment 20 and with the rear end portion 28 extended upward along the inside face of the rear wall portion 22 of the undergarment.

The crotch piece 25 is preferably formed of adjacent longitudinal halves of cloth material secured together by stitches along a longitudinal seam line 29. The peripheral edge portions of the crotch piece 25 are turned inwards and covered by a length of tape 30 secured in position 25 by spaced lines of stitches 31, see Fig. 5.

Means is provided for releasably attaching the end portions 27 and 28 of the crotch piece to the inside faces of the front and rear wall portions of the undergarment 20. This means comprises hooks 32, secured by pieces of cloth 33, to the end portions of the crotch piece 25. The hooks 32 are releasably engageable with complementary loops 34, see Fig. 2 mounted on the inside faces of the front and rear wall portions of the undergarment.

The hooks 32 are mounted on the end portions 27 and 28 of the crotch piece 25 intermediate the width thereof, and elastic straps 35 have their ends attached to the top corners of the end portions 27 and 28 of the undergarment so as to encircle the top portions of the wearer's legs beneath the undergarment 20, as shown in Fig. 1. Thus, the straps 35 assist the hooks 32 and the loops 34 in supporting the crotch piece in position. As shown in Fig. 5, the ends of the straps 35 are inserted in position between the adjacent faces of the turned peripheral edge portions of the crotch piece 25 and the tape 30 and secured in position by the same lines of stitches 31 which secure the tape 30 in position.

The top end edges of the crotch piece are inclined downward and outward from the hooks 32 to the top corners thereof where the ends of the straps 35 are secured to the top corners of the crotch piece 25.

It is believed that the method of donning the undergarment 20 having the removable crotch piece 25, in accordance with the present invention, will be obvious from the foregoing description. It will be appreciated that the undergarment may be provided with more than one of the crotch pieces 25, so that while one is being laundered the other may be used. As the crotch pieces become dirty and soiled more quickly than the undergarment 20, it is possible to remove the crotch piece 25 being used permitting it to be laundered independently of the undergarment. This will materially lengthen the life of the undergarment by reducing the number of washings to which it need be subjected.

In the modification of the invention shown in Figs. 6 and 7, the construction of the crotch piece 25 is similar to that of the previous form, differing merely in the provision of a means for ver-

4

tically adjustably and releasably securing the end portions 27 and 28 of the crotch piece to the inside faces of the front and rear wall portions of the undergarment 20. This construction permits the vertical position of the crotch piece 25 to be adjusted with relation to the undergarment 20 to a position which most comfortably suits the requirements of the wearer of the garment.

The inside faces of the front wall portion 21 and the rear wall portion 22 of the undergarment 20, in the modification of the present invention, are provided with vertical spaced lines of loops 34' with which the hooks 32 on the end portions 27 and 28 of the crotch piece 25 may be selectively engaged to secure the crotch piece 25 to the undergarment 20 at a desired elevated position.

In other respects this form of the invention is similar to that described in connection with the first form of the invention and like reference numerals identify like parts in each of the several views.

The modification of the invention shown in Figs. 8 and 9 is similar to that shown in Figs. 6 and 7, differing therefrom by the fact that the elastic straps 35' are each formed of separate sections 35^a and 35^b with means for adjustably connecting together the overlapped inner ends of the sections 35^a and 35^b so as to adjust the straps 35' to fit comfortably about legs of different circumferences.

The outer ends of the sections 35^a and 35^b of the straps 35' are secured to the top corners of the end portions 27 and 28 of the crotch piece 25 as in the previous forms of the invention. The inner end of the section 35^a of each strap 35', is provided with a pair of snap fastener elements 48 which are selectively engageable with two of four complementary snap fastener elements 41 mounted on the inner end of the section 35^b.

In other respects this form of the invention is similar to that shown in Figs. 6 and 7 and like reference numerals identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In combination with a lady's undergarment having opposed front and rear wall portions with inside faces, a separable crotch piece comprising a piece of cloth material having a narrow intermediate portion for extension beneath a wearer's crotch and wider front and rear end portions extended upward along the inside faces of the front and rear wall portions to have top corners located within the undergarment, opposed straps secured at their ends to the top corners of said front and rear end portions to engage about the wearer's legs beneath the undergarment, opposed vertical lines of spaced fasteners mounted on the inner faces of the front and rear wall portions, and single complementary fasteners mounted on said front and rear end portions midway between said top corners for selective engagement with desired fasteners of said vertical lines of spaced fasteners for vertically adjusting the position of said piece of cloth material with relation to the undergarment.

2. In combination with a lady's undergarment having opposed front and rear wall portions with inside faces, a separable crotch piece comprising a piece of cloth material having a narrow intermediate portion for extension beneath a wearer's crotch and wider front and rear end portions extended upward along the inside faces of the front and rear wall portions to have top corners located within the undergarment, opposed straps secured at their ends to the top corners of said front and rear end portions to engage about the wearer's legs beneath the undergarment, opposed vertical lines of spaced fasteners mounted on the inner faces of the front and rear wall portions, and single complementary fasteners mounted on said front and rear end portions midway between said top corners for selective engagement with desired fasteners of said vertical lines of spaced fasteners for vertically adjusting the position of said piece of cloth material with relation to the undergarment, each of said straps being formed of end aligned lengths of elastic material having adjacent ends overlapped and outer ends stitched to the top corners of said front and rear end portions, and complementary snap fastener elements on the adjacent faces of the overlapped ends of said lengths of elastic material for adjustably securing together said overlapped ends.

3. In combination with a lady's undergarment having opposed front and rear wall portions with inside faces, a separable crotch piece comprising a piece of cloth material having a narrow intermediate portion for extension beneath a wearer's crotch and wider front and rear end portions extended upward along the inside faces of the front and rear wall portions to have top corners located within the undergarment, opposed straps secured at their ends to the top corners of said front and rear end portions to engage about the wearer's legs beneath the undergarment, opposed vertical

lines of spaced fasteners mounted on the inner faces of the front and rear wall portions, and single complementary fasteners mounted on said front and rear end portions midway between said top corners for selective engagement with desired fasteners of said vertical lines of spaced fasteners for vertically adjusting the position of said piece of cloth material with relation to the undergarment, each of said straps being formed of end aligned lengths of elastic material having adjacent ends overlapped and outer ends stitched to the top corners of said front and rear end portions, and complementary snap fastener elements on the adjacent faces of the overlapped ends of said lengths of elastic material for adjustably securing together said overlapped ends.
